United States Patent Office.

C. B. GREGORY, OF BEVERLY, NEW JERSEY.

Letters Patent No. 77,082, dated April 21, 1868.

IMPROVEMENT IN COAL-STOVES.

The Schedule referred to in these Letters Patent and making part of the same.

TO ALL WHOM IT MAY CONCERN:

Be it known that I, C. B. GREGORY, of Beverly, Burlington county, New Jersey, have invented an Improvement in Stoves; and I do hereby declare the following to be a full, clear, and exact description of the same.

My invention consists of a stove, having an air-heating space or drum, and an external pipe, with a valve, all being arranged in the peculiar manner described hereafter, so that a greater amount of heat in proportion to the quantity of fuel consumed may be obtained from the stove than from those of the ordinary construction.

In order to enable others skilled in the art to make and apply my invention, I will now proceed to describe its construction and operation, reference being had to the accompanying drawing, which forms a part of this specification, and in which—

Figure 1 is a sectional elevation of my improved stove, and

Figure 2 a sectional plan view on the line 1-2, fig. 1.

A represents an ordinary cylindrical heating-stove, of which *a* is the ash-box, *b* the outer casing, *c* the fire-pot, and *d* the fire-door.

At the rear of the stove, and communicating with the interior of the same by two branches, *e* and *f*, is a vertical pipe, *B*, extending almost to the bottom of the stove, and open at its lower end, as shown, and within the said pipe, between its branches *e* and *f*, is a damper, *g*.

A casing, *C*, is suspended by stays *i*, or otherwise secured within the stove, and extends from a point a little above the fire-pot *c* to the top-plate *h*, and the lower front portion of the said casing is bevelled or inclined, as shown in fig. 1, so that access may be had to the fire through the door *d*.

A drum, *D*, of a form corresponding with but smaller in size than the casing *C*, is situated within the latter, and extends to the top-plate *h* of the stove.

The branch *e* of the pipe *B* communicates with the enlarged portion, *j*, of the chamber *F*, the latter being open at the top, as shown at *l*, fig. 1, and a short tube, *m*, extending from the outer casing, *b*, of the stove, to the lower end of the casing *D*, forms a communication with the interior of the latter, and in the top-plate *h* of the stove, directly over this casing, is an opening, *p*.

Cold air is admitted into the pipe *B* at a point close to the floor, and passes through the branch *e* of the pipe into the lower portion, *j*, of the chamber *F*, which is directly over the fire.

The air thus admitted to the chamber *F*, being brought into intimate contact with the casing *C*, (which is exposed to the direct action of the fire,) is intensely heated before it reaches the openings *l*.

The heated air taking this course necessarily imparts some of its heat to the drum *D*, into which cold air is admitted through the tube *m*, and is heated before it escapes through the central opening in the top of the drum.

The products of combustion from the fuel being dispersed laterally before escaping through the branch *f* to the vertical pipe, and being thus brought into intimate contact with the outer casing of the stove, increase greatly the amount of heat radiated from the same.

By adjusting the valve or damper *d*, more or less of the air which would otherwise pass into the space *F*, between the casings *C* and *D*, is permitted to pass directly through the vertical pipe to the chimney. Hence the quantity of heated air discharged from this space may be regulated at pleasure.

I claim as my invention, and desire to secure by Letters Patent—

1. The combination of the outer casing *A*, inner casing *C*, drum *D*, and the within-described openings for admitting cold air to and discharging it from the space between the casings *C* and *D*, and to and from the space within the drum, all as set forth.

2. The vertical pipe *B*, having a damper, *g*, situated between the opening *e* (for admitting cold air to the space between the casings *C* and *D*) and the branch *f*, through which the products of combustion pass to the said vertical pipe, as specified.

In testimony whereof, I have signed my name to this specification in the presence of two subscribing witnesses.

C. B. GREGORY.
